US00D995522S

(12) **United States Design Patent** (10) **Patent No.:** **US D995,522 S**
Bristol et al. (45) **Date of Patent:** **** Aug. 15, 2023**

(54) **CONTROLLER**

(71) Applicant: **Meta Platforms Technologies, LLC**, Menlo Park, CA (US)

(72) Inventors: **Peter Wesley Bristol**, Seattle, WA (US); **Yi-yaun Chen**, Seattle, WA (US); **Mauricio Romano**, Redmond, WA (US); **Peter Allan Chase Newbury**, Burlington, WA (US)

(73) Assignee: **Meta Platforms Technologies, LLC**, Menlo Park, CA (US)

(**) Term: **15 Years**

(21) Appl. No.: **29/865,455**

(22) Filed: **Jul. 26, 2022**

Related U.S. Application Data

(63) Continuation of application No. 29/818,223, filed on Dec. 7, 2021, now Pat. No. Des. 960,160, which is a (Continued)

(57) **CLAIM**

The ornamental design for a controller, as shown and described.

DESCRIPTION

FIG. 1 is a front perspective view of a controller showing the claimed design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown in the figures illustrate portions of the controller that form no part of the claimed design.

1 Claim, 8 Drawing Sheets

Related U.S. Application Data

continuation of application No. 29/723,794, filed on Feb. 10, 2020, now Pat. No. Des. 937,833.
